BRACELET

William Mueller, Milwaukee, Wis.

Application May 24, 1950, Serial No. 10,136

Term of patent 7 years

(Cl. D45—4)

To all whom it may concern:

Be it known that I, William Mueller, a citizen of no country, and a resident of Milwaukee, county of Milwaukee and State of Wisconsin, have invented a new, original, and ornamental Design for Bracelet, of which the following is a specification, reference being had to the accompanying drawing, forming part hereof:

I claim:

The ornamental design for a bracelet, as shown,

WILLIAM MUELLER.
